UNITED STATES PATENT OFFICE.

LAURITS AXEL PETERSEN, OF LOS ANGELES, CALIFORNIA.

CURRENT MOTOR.

Application filed June 4, 1924. Serial No. 717,762.

To all whom it may concern:

Be it known that I, LAURITS A. PETERSEN, a citizen of the United States, residing at Los Angeles, in the county of Los Angeles and State of California, have invented a new and useful Current Motor, of which the following is a specification.

This invention relates to a current motor, which is adapted to be supported in the water by means of floats, or to rest on the bed of a stream and to derive its power from the flow of the stream, or from the ebb flow of the tide.

The general object of the invention is to provide improved means for deriving the greatest possible amount of power from the current which is available, and especially where its flow is comparatively sluggish, but of considerable volume. The device is so arranged that any desired number of individual units may be used in connection with a single power shaft and may be operated by a current flowing in either direction.

The detailed construction and arrangement by which the objects of the invention are attained will be more specifically explained in connection with the accompanying drawings, which illustrate the same in its preferred form.

In the drawings:

Figure 1 is an end elevation of the invention.

Figure 2 is a vertical transverse section thereof.

Figure 3 is a plan view with parts shown in section.

Figure 4 is a vertical longitudinal section.

Figure 5 is a plan view of the central frame and water wheels carried thereby, with the gate shown in section.

Figure 6 is a vertical section taken on the line 6—6 of Figure 4.

Figure 7 is a detail perspective view of the gate.

The invention comprises an inner frame, which may be made either of wood or non-corrodible metal, and consists of a floor 11, with vertical longitudinal walls 12 at each side thereof forming a channel through which the current is directed. Two or more transverse bars 13 are secured within the channel and extend from side to side there-

of, and are provided with bearings 14 in which shafts 15 are journaled. The channel may be made of any size which the width and depth of the stream will permit, or according to the size of the power plant desired. Any number of shafts 15 may be used, and each of such shafts carries a water wheel 16 at each end, and adjacent thereto is an end plate 17 having circular openings 18 substantially corresponding in size to the diameter of the water wheels. If desired, a number of intermediate water wheels 19 may be secured to each shaft.

Secured at each end of the frame 10 is a mouth 20, having converging walls leading to the entrance of the channel, and provided with a screen 21 extending transversely thereacross, so as to prevent weeds or débris from becoming entangled with the water wheels.

The motor may rest on the bed of the stream, or it may be supported by floats in such a position that the water wheels will be substantially submerged. As shown in the drawings, it is supported by floats 22 arranged on opposite sides of the frame 10, and secured to the mouths 20 by brackets 23, soldered or otherwise held in fixed relation thereto. The floats are preferably so arranged with respect to the channel that they engage the upper edges of the walls 12, thus forming a part of the side walls of the channel and being disposed between mouths 20, so that they form practically no resistance to the current. The floats are further secured by means of semi-circular straps 24 held in clamping relation by bolts 25, and secured to the side walls 12 by means of brackets 26. The upper sides of the floats 22 are braced by transverse bars 27, which are secured to the upper ends of the respective straps 24.

As many units as desired may be employed to constitute a power plant, and each unit may contain any number of water wheel shafts 15, all connected to a common power shaft, as shown at 28. This power shaft may be supported in any desired position, and connected to the several water wheel shafts by any suitable gearing. In the embodiment shown in the drawings, the power shaft 28 is journaled in bearings 29 secured

to the bars 27, and each shaft 15 has a sprocket wheel 30 secured thereto, and connected by a sprocket chain 31 to a similar sprocket wheel 32 secured on the shaft 28. 5 The shaft 28 may be connected by a universal coupling 33 to a suitable power translating device, which may be reversible so that the motor may be driven by a current flowing in either direction through the channel. The floats 22 may be held against drifting by means of cables 34, the ends of which are connected with hooks 35 mounted on the bolts 25 at the upper ends of the clamping straps 24. 10 15 A gate 36 is provided for shutting off the current through the channel when power is no longer required. This gate is mounted to slide vertically between cleats 37 secured to the sides of the channel, preferably midway of its length. A bracket 38 is secured to the upper ends of the cleats 37 and extends upwardly therefrom, and a screw 39 secured centrally of the upper end of the gate extends upwardly through a hole 40 in the bracket. A wheel 41 is provided with a hub 42 resting on the upper end of the bracket 38, and into which the screw 39 is threaded, whereby a rotation of the wheel 41 in one direction will raise the gate, and 20 a rotation in the other direction will lower it. The gate is provided with vertical slots 43 and 44, through which the shafts 15 and 25 may pass.

From the foregoing description it will be seen that I have devised a current motor by which substantially all of the energy of the stream may be utilized. Even though the stream flows sluggishly, its velocity will be increased by the passage through the restricted channel, and the floats are so situated that they form substantially no resistance. Any number of units may be used, and so arranged as to utilize substantially all of the available current, and all may be connected to a single power shaft. While I have shown and described the preferred arrangement for effecting these results, it is to be understood that these are merely for the purpose of illustration, and that many modifications may be made within the scope of what is claimed without departing from the salient features of the invention.

What is claimed is:

1. In a current motor, the combination of 55 a frame forming a water channel, floats on opposite sides of the frame, clamps encircling the respective floats, brackets secured to the sides of the frame and to the lower ends of the clamps, transverse bars located 60 above said frame and connecting the upper ends of the clamps, a plurality of parallel longitudinal shafts mounted within the channel and each having one or more water wheels thereon which are normally submerged, bearings supported by said trans-

verse bars, and a power shaft journaled in said bearings parallel to the water wheel shafts and operatively connected thereto.

2. In a current motor, the combination of 70 a frame forming a water channel, a mouth at each end of the channel with converging walls leading to the channel, a plurality of longitudinal shafts journaled within the channel and having water wheels at each end thereof, a plate extending across each end of the channel with circular openings in front of each water wheel and of substantially the same size as said water wheel, a float at each side of the frame and contained 75 within the space between said mouths with the inner sides of the floats forming upward extensions for the side walls of the channel, clamps encircling the respective floats, brackets secured to the side walls and to the lower extremities of the clamps, transverse bars connecting the upper extremities of the clamps, bearings supported by said bars, and a power shaft supported for rotation 80 in said bearings and operatively connected to each of the water wheel shafts.

3. In a current motor, the combination of 85 a frame forming a channel with bottom and side walls, a mouth at each end of the channel with converging walls leading to the channel, a plurality of longitudinal shafts journaled within the channel and having water wheels thereon, floats located at each side of the frame and contained within the 90 space between the walls of said mouths, clamps encircling the respective floats, brackets secured to the side walls of the channel and to the lower extremities of the clamps, transverse bars connecting the upper extremities of the clamps, bearings supported by said bars, a power shaft journaled 95 in said bearings and operatively connected to each of the water wheel shafts, cleats secured to the inner sides of the channel walls and forming vertical opposed guideways, a gate mounted in said guideways and 100 having vertical slots through which said shafts pass, and means for raising and lowering said gate.

4. In a current motor, the combination of 105 a frame forming a channel with bottom and side walls, a mouth at each end of the channel with converging walls leading to the channel, a plurality of longitudinal shafts journaled within the channel and having water wheels at each end thereof, a plate extending across each end of the channel with circular openings in front of each water wheel and of substantially the same size as the water wheel, a float at each side of the frame and contained within the space between the walls of the mouths with the inner sides of the floats forming upward extensions 110 for the side walls of the channel, clamps encircling the respective floats, brackets secured to the side walls and to the lower extremities of the clamps, transverse bars connecting the upper extremities of the clamps, bearings supported by said bars, a power shaft journaled 115 in said bearings and operatively connected to each of the water wheel shafts, cleats secured to the inner sides of the channel walls and forming vertical opposed guideways, a gate mounted in said guideways and having vertical slots through which said shafts pass, and means for raising and lowering said gate.

120

125

130

extremities of the clamps, transverse bars connecting the upper ends of the clamps, bearings supported by said bars, a power shaft journaled in said bearings and oper-
5 tively connected to each of the water wheel-
shafts, cleats secured to the inner sides of
the floats and the channel walls and form-
ing vertical opposed guideways, a gate
mounted in said guideways and having ver-
tical slots through which said shafts pass, ¹⁰
and screw threaded means for raising and
lowering said gate.

In testimony, that I claim the foregoing
as my own, I have hereto affixed my sig-
nature.

LAURITS AXEL PETERSEN.
